J. R. ROSE AND EDWARD L. CALEY, JR., OF PHILADELPHIA, PENNSYLVANIA,
ASSIGNORS TO WILLIAM E. WOOD & CO., OF BALTIMORE, MARYLAND.

Design No. 3,764, dated November 23, 1869.

DESIGN FOR THE BORDER-FRAME OF A FIRE-PLACE.

The Schedule referred to in these Letters Patent and making part of the same.

We, J. R. ROSE and EDWARD L. CALEY, Jr., of the city of Philadelphia, in the State of Pennsylvania, have invented and produced a new and original Ornamental Design for the Border-Frame for a Fire-Place Stove, of which the following is a specification.

The nature of our invention or design is fully represented in the accompanying photographic illustration, to which reference is made, the part constituting the design being indicated by the letters A B C, marked thereon.

Claim.

We claim as our invention, the design for a border-frame for a fire-place stove, as shown and specified.

J. R. ROSE.
EDW. L. CALEY, JR.
